UNITED STATES PATENT OFFICE.

CHARLES HUGHES, OF NEW YORK, N. Y.

AUTOMATIC FIRE-LIGHTER.

SPECIFICATION forming part of Letters Patent No. 319,722, dated June 9, 1885.

Application filed October 11, 1884. (No model.)

To all whom it may concern:

Be it known that I, CHARLES HUGHES, of the city, county, and State of New York, have invented a new and Improved Automatic Fire-lighter, of which the following is a full, clear, and exact description.

The object of my invention is to provide a new and improved automatic fire-lighter which lights the fire at any desired time.

10 The invention consists in the combination, with an alarm-clock mechanism, of a spring-actuated lever adapted to hold a match and a piece of inflammable material, a trigger for locking the lever, which trigger is operated 15 by the clock-work mechanism, and of a rod pivoted on the clock-casing and carrying a plate on which a piece of sand-paper or like material is held, all as hereinafter fully described, and pointed out in the claims.

20 Reference is to be had to the accompanying drawings, forming part of this specification, in which similar letters of reference indicate corresponding parts in all the figures.

Figure 1 is a face view of my improved fire-lighter, parts being broken out. Fig. 2 is a cross-sectional view of the same. Fig. 3 is a plan view.

25 On the notched disk A of an alarm-clock of the usual construction one end of a pivoted 30 lever, B, rests, acted upon by a spring, C, which presses the free end of the lever upon the edge of the disk.

A rod or wire, D, having its upper end connected with the lever B, has its lower end connected with a trigger-lever, E, pivoted on a frame, E', projecting from the inner surface of one side of the clock-case A'.

35 On a shaft, F, journaled in the frame E, are rigidly mounted a pinion, G, and a lever, H, 40 projecting through a vertical slot, H', in the back of the casing A'. The pinion G engages with a cog-wheel, J, mounted on a shaft, K, to which one end of a spiral spring, L, is secured, the other end being fastened to the frame E'.

45 On the outer end and upper edge of the lever H two pairs of spring jaws or clamps, M, are secured, which are adapted to hold a match, N, the head of which projects beyond the end of the lever.

50 A hook or prong, O, projects downward from the free end of the lever.

A plate, P, forming a socket, P', is secured on the back of the casing A' and receives the bent inner end of a rod, Q, to the free end of which an arm, R, is pivoted, carrying a downwardly-inclined spring-frame, I, and a vertically-swinging plate, S, resting on the spring-frame and provided at its upper end with two pins, T.

The socket P' has a notch in the top of its outer side.

The operation is as follows: The alarm mechanism is set in the usual manner, a match, N, is placed in the spring-clamps M, and the outer end of the lever H is raised until its inner end 65 is engaged by the trigger E. By raising the lever H the pinion G, the wheel J, and the shaft K are turned and the spring L is tightened. A piece of sand-paper or like material is held on the plate S by means of the pins T, 70 and a piece of paper or other very combustible material is held on the hook or prong O on the free end of the lever H. The casing A is then placed directly in front of the stove, so that when the paper or combustible material 75 on the hook O burns it can ignite the fuel in the stove. At the time for which the clock has been set the notch on the disk A comes under the free end of the lever B, the spring C forces the lever B downward, and by means 80 of the rod D swings the trigger-lever from the inner end of the lever H, which is forcibly swung down by the spring L, whereby the match is rubbed over the sand-paper on the plate S and ignited, and in turn ignites the 85 paper or other combustible material on the hook O.

The rod Q is held in place to project from the back of the casing by being passed into the notch in the top of the socket.

90 When the apparatus is not in use, the rod Q is raised slightly and then swung against the back of the casing, the arm R being also swung against the back of the casing, as shown in dotted lines in Fig. 3.

95 Having thus described my invention, what I claim as new, and desire to secure by Letters Patent, is—

1. In an automatic fire-lighter, the combination, with an alarm-clock-work mechanism, 100 of the lever B, the rod D, the trigger E, the match-holding lever H, the pinion G, the cog-

wheel J, and the spring L, substantially as herein shown and described.

2. In an automatic fire-lighter, the combination, with a clock-work mechanism, of the trigger E, the rod or wire D, the lever H, the pinion G, the cog-wheel J, the clamps M on the lever H, and the hook O on the lever H, substantially as herein shown and described.

3. In an alarm-clock, the combination, with a clock-work mechanism, of the lever H, a

spring acting on it, the rod Q, pivoted on the back of the clock-casing, the arm R, pivoted to the rod Q, and a plate, S, held on the arm R and provided with pins T for holding a piece of sand-paper or analogous material.

CHARLES HUGHES.
